UNITED STATES PATENT OFFICE.

STEPHEN JARVIS ADAMS, OF PITTSBURG, PENNSYLVANIA, ASSIGNOR TO
MARCELLIN C. ADAMS, OF PITTSBURG, PENNSYLVANIA.

APPARATUS FOR FORMING SAND MOLDS.

SPECIFICATION forming part of Letters Patent No. 704,951, dated July 15, 1902.

Application filed May 11, 1894. Serial No. 510,846. (No model.)

To all whom it may concern:

Be it known that I, STEPHEN JARVIS ADAMS, a resident of Pittsburgh, in the county of Allegheny and State of Pennsylvania, have invented a new and useful Improvement in Apparatus for Forming Sand Molds; and I do hereby declare the following to be a full, clear, and exact description thereof.

My invention relates to apparatus for forming sand molds; and its object is to provide especially rapid means for forming sand molds, having in or on one side thereof one mold-face and on the opposite side another mold-face, the respective mold-faces of a series of molds fitting together so as to make a completed mold-cavity—such, for example, as in connection with molds for brake-shoes, which, as described in an application for patent filed by me on the 24th day of October, 1892, Serial No. 449,904, are arranged so that the molds are inclosed within flasks which stand on end, and the two faces of the respective molds are placed together to form the mold-cavity.

The object of the invention is to perform by certain automatically-working apparatus under the control of the workmen the necessary steps for rapidly making molds of this kind.

The invention consists, generally stated, in apparatus for forming these sand molds whereby two irregular faces may be formed, one corresponding with one mold and the other with another, this being accomplished by the employment of a cutter which cuts or planes off one side or face of the mold to irregular shape, a confining-plate which confines that face of the mold to irregular shape, and a pattern which is forced in from the opposite face of the mold and which serves to compact the sand between such confining-plate and pattern.

The invention further relates to apparatus for the formation of molds having dovetailed seats in their bases, which is a desirable form of mold for brake-shoes, which consists in spreading dovetailed-pattern parts carried by the main pattern, then forcing up the pattern carrying these parts into the sand within the flask to form the mold, then drawing in the

dovetail-pattern parts, and then withdrawing the main pattern carrying these parts.

The invention also consists in apparatus used in the making of the molds, which will be hereinafter described, the apparatus being so constructed that all the different operations and the handling of the pattern controlling its different movements and controlling the movements of the dovetailed portions carried thereby and the movement of the different parts at the proper times are all brought within the control of the operator by means of a couple of levers.

To enable others skilled in the art to understand my invention, I will describe the same more fully, referring to the accompanying drawings, in which—

Figure 1 is a face view of the machine proper, and Fig. 2 an end view thereof. Fig. 3 is a top or plan view thereof. Fig. 4 is a cross-section on the line 4 4, Fig. 1, illustrating, in connection with the machine, the clutch or like controlling mechanism employed therewith for giving the necessary movements. Figs. 5 and 6 are longitudinal sections of the upper part of the machine, illustrating the operation of making the mold. Fig. 7 is a vertical cross-section of the machine, illustrating the operation thereof and also showing the cams for controlling the movement of the machine. Fig. 8 is a like cross-section of the upper part of the machine, illustrating the withdrawal of the wing-patterns. Fig. 9 is a face view of the driving mechanism. Fig. 10 is a perspective view illustrating the cutting off of the upper face of the mold. Figs. 11 to 14 are detail sectional views illustrating the operations of forming the mold. Fig. 15 is a perspective view of the top confining-plate. Fig. 16 is a perspective view of the guard-plate for the mold. Fig. 17 is a detail view illustrating the withdrawal of the mold from the machine. Fig. 18 is a perspective view of the mold formed. Fig. 19 is a sectional view of a line of molds. Fig. 20 is a side view of a line of molds, and Fig. 21 is a view of the finished brake-shoe.

Like letters of reference indicate like parts in each of the drawings.

The machine embodying the invention is

formed of a frame A, composed of the bed-plate A', standards A², and top plate A³, as well as suitable cross-beams A⁴ A⁵, extending between the standards to brace the machine and form supports for the bearings. Extending between the upper cross-beams A⁴, from one end of the machine to the other, is the bearing-bar a, having guideways in which the upper portions of the longitudinally-moving bars imparting the necessary motion to the pattern or other parts are mounted, and a like bearing-bar a' extends between the lower cross-beams A⁵, having guideways in which the lower portions of said bars are also mounted. As shown in the drawings, the stripping-plate b is connected to the outer cam-bars B through the vertical blocks b², which extend down at the front and rear of said stripping-plate b and rest on the horizontal skeleton frame b³, to which the cam-bars B are connected. Said cam-bars B extend down into the course of the cams B' on the power-shaft D, mounted in bearings at the lower end of the main frame A, suitable friction-rollers b⁴ being preferably secured at the end of the cam-bars B and traveling on the cams B'. The patterns c are carried by a frame C², formed of the upper pattern-plate c', having blocks c² at the ends thereof, resting on the lower pattern-plate c³, which fits within the skeleton frame b³, to which lower plate c³ the cam-bars C are connected, said cam-bars moving in guideways in the bearings a a' and having at the lower ends thereof the friction-wheels c⁴, which engage with the cams C' on the shaft D for operating the patterns.

The parts above described might be termed the "main operative parts" of the machine, and I will now describe the general construction of the machine, so as to more clearly illustrate the improvements embodied therein.

It will be seen that the machine is illustrated in connection with the formation of molds for making brake-shoes, and in the making of such a mold it is necessary that there shall be a flask in which the mold is to be formed and a proper means to support the same, and I will therefore first describe such parts. The flasks E are preferably made of cast-iron, so as to prevent warpage or any action which would throw them out of line, and they rest upon the table A³; but inside and supported on the said table is the removable and interchangeable flask-supporting plate e, which corresponds in shape to the edge of the flask, it being preferred, as described in the application above referred to, to employ a flask the edges of which are irregular and which corresponds approximately to the shape of the mold to be formed, so as to give better support thereto. As the invention is illustrated in connection with the making of brake-shoes which have one face concave, corresponding to the curve of the wheel, and the body made on substantially the same curve, the flasks E have the end walls e' and the side

walls e², the central edges of which side walls are curved, corresponding to the curve or general contour of the brake-shoe—that is, they have on one edge the curved projecting portion e³ and at the other edge the curved depression e⁴. The flask-plate e corresponds in shape to the lower edge of the flask, having a curved projection e⁵ fitting into the curved recess e⁴ of the flask-body, and so closing that part of the flask. The interior faces of the flask and of the flask-plate correspond, and the flask-plate e has the downwardly-hanging flange e⁶, forming a pocket or reservoir for sand below the flask, the base of which reservoir is formed by the stripping-plate b. The flask-plate e carries guides e⁷ for centering the flask E upon the flask-plate. As the two faces of the molds beyond the mold-cavities must of course correspond with each other, and in this method of molding the face on one side of the mold is a counterpart of the other and the stripping-plate b forms the mold-face around the mold-cavity, this stripping-plate corresponds in outline to the two corresponding faces to be formed upon the mold, and therefore has the curved projecting portions b' on each side of and between the patterns c, which impart the necessary curvature or form to the mold-face to fit the opposite face of the adjoining mold. The other or opposite surface of the mold is formed by a plate irregular in shape and corresponding to the mold-face desired to be formed. This plate F is shown in Fig. 1 as resting on the flask E and in some of the other figures as passing through a shallow reservoir resting on the flask, as at E', this reservoir being sometimes used where found desirable, as hereinafter described. In either case the top plate F corresponds to the one face of the mold to be formed, having in the mold shown the curved depression f, corresponding to the curved portion e³ of the flask and corresponding to the curve of the brake-shoe face. Whether this top plate F rests directly upon the flask E or upon the shallow reservoir or sand-holder E', its molding position is even with the top edge of the flask, in the latter case the top plate being forced downwardly through the shallow reservoir E' before the pressing operation takes place, and the top plate having lips extending out over the shallow reservoir E', so as to guide it to proper place. The top plate F is illustrated as having a rib f² therein to form a runner on that mold-face. This runner may also be formed by a projection on the stripping-plate b, if desired, a plain top plate of the desired curve or general outline being used. Such rib, however, serves to illustrate any desired projection to form any desired cavity in that mold-face.

One of the requisites for rapid-molding operation is the rigid support of the flask and top plate during the pressing operation and free space for work with the flask before and after the pressing operation. These two requisites I obtain by the employment of a swing-

ing frame above the main frame, carrying the resistance-plate F'. This resistance-plate F' is supported in the horizontal beam G, mounted on the vertical post G', extending up from the main frame, the beam G swinging on said post between adjustable collars G² on the post and the beam having at its outer end a bracket G³, from which the brace-rod G⁴ extends to the upper end of the post G' and is connected to a collar G⁵, fitting around the same. The beam G has at the right end thereof the handle-bar g, by which it may be swung horizontally on the post. It has also at the opposite or free end the stirrup g', which extends down from the post and engages with a hook g² upon the table, so that when the brace-beam G is swung over, so that its stirrup engages with said hook, this brace-beam is rigidly supported as against vertical strain by its post G' and its stirrup g'. To carry the flasks containing the molds over this hook, I employ a rocker g⁷, extending up from the table A³ and preferably having an angular upper end which fits in notches or recesses g⁸ in the lower corner of the flask, so forming a fulcrum for the turning over of the flask, so that it may be rocked over hook g² on the table and onto the extension or side table T' in position to receive any necessary cores. To protect the mold in this operation, a guard-plate A⁶, corresponding substantially to the shape of the upper face of the mold, is first placed upon the flask and the flask rocked over until it rests thereon. This guard-plate has lugs y y' y² fitting above, below, and at the side of the flask to hold it in position thereon and has also handles y³ for carrying the flask by means of the guard-plate and placing it on the foundry-floor, as shown in Fig. 20. It will be noticed in said figure that the flasks have guide-lips y⁴ projecting out therefrom and fitting against guide-lugs y⁵, by which the flask when carried out by the guard-plate is directed to exact position in the line of molds. It will also be noticed that the lower edges of these flasks, diagonally opposite the projecting guide-lips y⁴, rest upon the support, while the bases directly under said projecting guide-lips recede, so that each flask when placed in position rests upon its outer lower corner y⁶, while its corner close to the mold against which it is placed is raised from the support, and there is therefore a tendency of the flask with the mold therein to press against the mold in building up the row or series of molds, the outer lower ends y⁶, above referred to, so forming supporting-bearings for the flask only at one side of the lower end thereof and causing such flask to swing or press against the adjoining flask. The resistance-plate F' has guide-bars g⁹ extending through the beam G. A threaded shaft g¹⁰ passes through a like threaded passage in the beam or sleeve secured therein and has a swiveling joint g¹¹ with the resistance-plate, and said shaft is turned by the hand-wheel g¹².

In the formation of molds it is very desirable that the amount of sand to be compressed in any part of the mold shall be such that when the pressure is applied it will be evenly compacted throughout, and as the patterns for the brake-shoes are formed on a curve, as above stated, and the top surface of the mold is to be curved, as above stated, I bring the top surface of the mold before it is compressed to substantially the form of the finished mold—that is, I even off the sand so that its top face is irregular in shape, corresponding substantially in shape to the top plate F. This I accomplish by placing on the flask E or on the shallow flask E', which may be employed, as above stated, a feeding-reservoir H, having its lower edge formed with a curved depression h, corresponding in shape to the depression f in the lower face of the top plate F, and having along the front inner edge thereof a cutter or planer h'. The sand is filled into this feeding-reservoir H, it being preferred that the sand be fed from a suitable overhead carrier, so that it is brought into the mold-cavity in a mealy condition, and as soon as the mold is filled to the proper height the operator slides off said top reservoir H over the surface of the flask, which planes or cuts off the sand to a shape corresponding to the lower face of the top plate F. In order to hold the reservoir H in line for such planing or cutting-off operation, guide-ways h² are arranged back of the flask, being supported on the table A³, and the feeding-reservoir H travels along such guide-ways, which correspond in line to the top of the flask or shallow reservoir E', resting thereon, so giving support to the feeding-reservoir H in its stroke across the flask. The sand which is cut or planed off in this way passes down the chute h³ into a suitable hopper and may be carried back again to the overhead hopper. This cutter working to cut off the sand to an irregular shape corresponding to one mold-face may be employed in cutting off the sand after it has been compacted, as described in a patent granted to me December 29, 1896, No. 574,052. It will thus be seen that in the formation of the molds the patterns c extend up within the molding-space of the flask and the stripping-plate b fits around such pattern, leaving below the flask the sand-space b¹ around and between the patterns, this being the position in which the parts of the molding apparatus rest in preparing to make the mold, and the steps being to place the flask upon the flask-plate, place the feeding-reservoir H thereon or on the shallow flask E' above it, as desired, feed the sand into the molding-space, slide the feeding-reservoir H over the flask, so bringing the top of the sand to the proper contour and discharging the surplus sand down the chute h³, place the top plate F upon the flask, (or, if the shallow reservoir E' is used, force it down through such reservoir until it is even with the top edge of the flask,) by the han-

dle g swing the beam G over the flask until its stirrup g' engages with the hook g'' on the table, and by the hand-wheel g^6 force the resistance-plate F' down upon the top plate F 5 to hold the parts rigid, when the apparatus is ready for the pressing operation.

The apparatus shown is for the purpose of forming the brake-shoe molds, and it is preferred to employ it for forming molds for 10 casting brake-shoes having dovetailed faces thereon, as shown in Fig. 21.

I will now describe the method of forming the brake-shoe having the dovetailed wings i^1 , the shoulder i^2 at the upper end of the 15 wing i , and a slot i^3 , extending through the wing i on the back of the shoe. The slot i^3 is formed by means of a core and does not require special description, its use being to lock the brake-shoe upon the holder. The 20 body of each pattern c is formed hollow and to form the shoulder i^2 has the projection c^5 , and the pattern also has a slot c^6 extending from said projection c^5 to the other end of the pattern. Moving vertically in said slot 25 is the pattern-block k , said pattern-block extending between the wing-patterns k' , which are hinged near the base of the hollow pattern c , and extend up through the slot c^6 , the wings k' always extending through the 30 slots. Said wings are pivoted at k^2 within the hollow pattern c , and the arms k^3 thereof extend up and connect to the dovetailed portions k' , which extend beyond the pattern. Said arms have extending horizontally from 35 the bases thereof the fingers k^4 , which enter slots in the pattern-block k , so that when the pattern-block is drawn down the top walls of said slots will strike the fingers k^4 and draw the dovetailed portions k' inwardly toward 40 each other; but when the pattern-blocks k are raised they will pass between the dove-tailed wing-patterns k' and spread the same and hold them rigidly in place during the molding operation. It will be noticed that 45 at the point of connection between the wing-patterns k' and their arms k^3 there is an incline k^6 , and the pattern-block k strikes these inclines as it is forced up between the wing-patterns k' . Each pattern-block k is carried 50 on vertical bars k^7 , which extend down through the frame c^8 , carrying the patterns, and are connected to the plate K , operated by the hand-lever K' , which connects by the strap K^9 with the plate K , so providing for 55 the upward-and-downward movement of the pattern-blocks k and the spreading or inward movement of the wing-patterns k' . The lever K' is pivoted on a bar K^5 , depending from the plate c^8 . The movement of the lever K' is controlled by the stops K^3 and K^4 60 on another depending bar K^6 , the pattern-blocks k and other of said parts moving with the main patterns, except when said lever K' is operated to withdraw or spread the wing-patterns k' , as hereinafter described.

In order to insure the withdrawal of the patterns from the finished mold after the

molding operation, I provide the weighted lever J , which is pivoted at J' to the main frame or a bracket J^2 , secured thereto, and 70 carries at its forward end the weight J^3 , the said lever having also the roller J^4 , which travels on the cam J^5 on the power-shaft D . This lever is connected by a bar J^6 , sliding in a yoke J^7 , with the cam-bars C operating 75 the patterns, so that the weight of the lever operates upon the same to cause the withdrawal of the patterns in case they are struck within the molds.

It is not considered necessary to describe 80 the shapes of the several cams on the cam-shaft D further than to state that they are set to operate to give the desired motions in the operation of forming the mold and withdrawing the pattern parts therefrom. 85

The pressing operation is substantially as follows: After the filling of the flask and the reservoir-space b^4 above the stripping-plate and the securing of the top plate F above the same, as above described, the cams operate 90 in substantially the following way: The movement of the patterns in forming the mold is somewhat shorter than that of the stripping-plate, and the patterns and stripping-plate travel together at about the same 95 speed until the patterns are raised to their full height, and as it is desirable to have the sand packed firmly around the edges of the mold-cavities and in the front face of the mold the stripping-plate b continues to move after 100 the pattern ceases for a short distance until the stripping-plate is brought even with the flask-plate, substantially as shown in Fig. 6. During this time it is of course understood 105 that the dovetailed wings k' are spread apart and the pattern-blocks k are in their raised position to form the desired pattern for the entire mold. The operator then grasps the lever K' and presses down on the same, which withdraws the pattern-blocks k and draws in 110 the wing-patterns k' , so that the pattern can be withdrawn, leaving the dovetailed seats in the mold. The cam-shaft D is then started, and it withdraws the patterns while the stripping-plate is held in its raised position, 115 the weight of the lever J operating to insure the withdrawal of the patterns. As soon as the patterns are withdrawn the operator then raises the pattern-blocks k and spreads the wing-patterns k' to prevent the sand from 120 entering the hollow patterns, and he then disengages the top plate F from the flask, places the guard-plate A^6 on the flask, and rocks it over from the pattern-plate in position to receive the cores. The mold so made has one 125 face formed by the top plate F , which has been packed by the pressure of the sand against that plate as the patterns were raised, and the other face having the cavities j formed therein by the patterns, the two faces 130 being thus formed in the mold at one operation. If desired, some slight depressions or projections can be formed by means of the top plate F , the hollow portion f of the same

giving the curved face for forming the concave face of the brake-shoe and, as shown in one of the figures, the rib f^2 extending along the plate to form the runner leading to the 5 mold-cavities. The operator then starts the cam-shaft, the result of which is that the stripping-plate is drawn back to its lowest position and the mold is ready to again receive sand. For certain classes of molds, where it 10 is desirable to withdraw the pattern entirely, so that it will not interfere with the removal of the finished mold, the pattern may be withdrawn below the mold, and after the mold is withdrawn from the machine as the stripping-plate is drawn down the pattern may be 15 raised again a short distance to bring it into proper position to receive sand.

In Figs. 11 to 14 the different positions of the pattern and stripping plate are shown in 20 diagram views, Fig. 11 showing the position to receive sand, the patterns extending slightly into the flask, the stripping plate being at its lowest position, so as to form the reservoir b^4 below the flask; Fig. 12 showing the upward 25 movement of the pattern and stripping plate and the point at which the pattern stops, the stripping-plate not having reached its highest position; Fig. 13 showing the stripping-plate raised to its highest position, Fig. 14 showing 30 the pattern withdrawn to its lowest position, the stripping-plate remaining in its highest position, and the next position being that shown in Fig. 11, the pattern being again raised and the stripping-plate lowered, the 35 parts being again brought into position to receive sand.

It is necessary for the proper operation of the apparatus that the cam-shaft shall be turned into exact position and then stopped, 40 so as to provide for filling in the sand, withdrawal or projection of the wing-patterns, removal of the mold, &c., and that the parts be drawn to these different positions and held there, so that the molder controls these positions by the movement of the levers, and it 45 is very desirable that the machine be arranged to be operated by unskilled labor. I will now describe the driving mechanism and the manner in which these results are obtained, first stating that the movement of the machine is controlled by two hand-levers—to wit, the lever L , controlling the movement of the cam-shaft, and the lever K' , controlling the movement of the pattern-block k and 50 wing-patterns k' . The cam-shaft D carries the large gear-wheel d , which is driven by the pinion m on the driving-shaft M . This driving-shaft is mounted in bearings m' in the frame M' and is driven by a belt upon 55 the pulley M^2 , running loosely on the driving-shaft M . Secured to the pulley M^2 and turning with it on the power-shaft is the friction-clutch member M^3 , and secured to the shaft M is the collar m^2 , having the arms m^3 , carrying clutch-arms m^4 , which have friction-faces m^5 , adapted to contact with the clutch member M^3 . Sliding on said shaft M and con-

nected thereto by a feather is the collar n , between which and the clutch-arms m^4 are the toggle-arms n' , so that by the longitudinal movement of the collar n the clutch-arms m^4 are thrown into contact with or withdrawn from the clutch-face M^3 . Any other suitable form of clutch may be employed. Mounted 70 on the frame M' is the lever N , which is operated by the rod N' , connected to the arm l of the vertical operating-shaft L' , at the upper end of which is the hand-lever L , above referred to. The lever N is connected to the sleeve n by means of a collar n^2 , fitting around 75 said sleeve, so as to move the same longitudinally while permitting the rotation of the sleeve n , it being evident that when the hand-lever L is moved by the operator through the arm l , rod N' , and lever N the toggle-arms n' are straightened out, so as to force the clutch-arms m^4 into contact with the clutch member M^3 and cause the turning of the power-shaft M by the pulley M^2 . The vertical shaft L' is mounted in brackets l' , and in addition to 80 the arm l it carries the arm p , which is connected to the rod p' , which extends to the brake-bar P . This brake-bar is mounted in the bearing p^2 and extends over the friction-drum P' on the driving-shaft M and has the 85 brake-shoe p^3 resting on the friction-drum P' , the brake-bar P carrying at its free end the weight P^2 . The rod p' extends from the arm p to the sliding bar p^4 , which moves in a guideway p^7 under rollers p^5 and above the 90 forward end of the brake-bar P , and said sliding bar p^4 has on it the inclined face p^6 . When the sliding bar p^4 is moved backwardly 95 by the hand-lever L , arm p , and connecting-rod p' , it travels longitudinally in the guideway p^7 , and the incline p^6 thereon passes over the forward end of the brake-bar P , depressing that end of the bar, and therefore raising the part on the other side of the bearing p^2 and raising the brake-shoe p^3 from contact 100 with the friction-drum P' , so leaving the driving-shaft M free to turn. 105

It will be noticed that on the cam-shaft D is the disk R , which turns with that shaft and has a series of knockers $r^1 r^2 r^3$ thereon. 115 Mounted on the hand-lever L is the hand-trigger r^4 , which connects by the rod r^5 with the lever r^6 , mounted in the bracket l^3 on the vertical shaft L' , and extending from the opposite end of the lever r^6 to the pivoted dog 120 or block r^7 is the connecting-rod r^8 , the pivoted dog r^7 being mounted in the arm l^4 , secured to the vertical shaft L' , said dog r^7 extending into the course of the knockers $r^1 r^2$, &c., on the disk R . Connected to the pivoted 125 dog r^7 is the spring r^9 , which holds that dog normally in the course of the knockers $r^1 r^2$, &c., on the disk R . When the operator desires to cause the movement of the cam-shaft, he grasps the hand-lever L and the trigger 130 r^4 , draws on the trigger, which through the connecting-rod r^5 , lever r^6 , and connecting-rod r^8 draws the pivoted dog r^7 out of the course of the knockers on the disk R . He

then pulls on the lever for its full stroke, which is the same in every case, by which operation the vertical operating-shaft L' is turned, which through the mechanism above described applies the clutch-arms m^4 to the clutch-member M ^{3} and through the sliding bar p ^{4} raises the brake-shoe p ^{3} from the friction-drum P', so leaving the power-shaft free to turn, and the power is applied from the pulley M ^{2} to the driving-shaft and thence through the gearing m d to the cam-shaft, which is turned for a part of a revolution. The operator has in the meantime released the hand-lever L and trigger r ^{4} , and the pivoted dog r ^{7} has dropped into the course of the knockers on the disk R, and the machine continues to operate until one of the knockers strikes this dog r ^{7} and carries it, with the arm l ^{4} , on which it is mounted, around with it, so turning the vertical shaft L' and carrying the hand-lever L back to its starting-point and at the same time through said shaft and its connections opening the friction-clutch and drawing on the sliding bar p ^{4} , so that the incline p ^{6} is drawn out of the course of the brake-bar P, permitting the brake-shoe carried by such bar to contact with the friction-drum P', so stopping the machine. It will be understood that the knockers on the disk R are spaced according to the desired rotation of the cam-shaft and that the operator is only required to draw on the hand-lever L for its full stroke, when by the mechanism above described when the cam-shaft has been turned for the desired distance the clutch will be opened, the brake applied to the power-shaft, and the machine stopped. It is also necessary to the proper working of the machine by unskilled labor that it shall be locked in such a way that the operator cannot make mistakes in the operation, such as the withdrawal of the pattern without first drawing in the wing-patterns (in which case the mold would of course be spoiled) and the operation of the machine without again closing the mold by throwing out the wing-patterns, (as, if said mold were left open, sand might collect therein and clog that part of the machine.) For this purpose I provide the locking-bars S S', which are mounted at s s' on the machine-frame A and extend back into the course of the hand-lever K' and have connected to the rear ends thereof the springs s ^{2} s ^{3} , respectively, the ends of said springs being connected to the bearing-plates a a', respectively, stops s ^{4} s ^{5} being provided, against which the rear ends of said locking-arms are held. At the forward or outer ends of said locking-bars are the inwardly-extending lips S ^{2} S ^{3} , which extend toward each other, and in their normal positions these locking-bars stand with said inwardly-projecting lips above and below the locking-arms S ^{4} on the vertical operating-shaft L', permitting said locking-arms to pass between the lips on the locking-bars. As above stated, the lever K' is controlled by the movement of the patterns, and when thrown into one or the other posi-

tion it is moved up and down as the patterns rise and fall, so that when the patterns rise in the pressing of the mold they carry up with them the frame K and the lever K', mounted thereon. As they rise this lever K' strikes the upper locking-bar S and raises that bar, so as to lower the outer end thereof and bring the downwardly-projecting lip S ^{2} thereof into the course of the locking-arm S ^{4} on the vertical shaft L'. The next step in the making of the mold is the movement of this lever K' to draw in the wing-patterns k'; but if the operator should again attempt to draw upon the hand-lever L and turn the shaft L' as the lip S ^{2} has been thrown into the course of the locking-arm S ^{4} said arm will strike said lip and the operator cannot move the hand-lever L. He must therefore first depress the lever K', which is drawn away from the locking-bar S, so that the spring s ^{3} draws the lip on said bar out of the course of the locking-bar S ^{4} . The next operation is to again draw on the hand-lever L, which causes the withdrawal of the patterns from the completed mold, and said lever K' will move downwardly as the patterns are withdrawn and contact with the locking-bar S' and throw its lip S ^{3} into the course of the locking-arm S ^{4} , so that the operator cannot move the hand-lever L until he has raised the hand-lever K', and so forced the pattern-block k between the wing-patterns k', so spreading the wings to their normal position and closing the cavity leading into the hollow pattern. As soon as this is done the operator can again draw on the hand-lever L, which causes the withdrawal of the stripping-plate and, if necessary, the advance of the patterns to the position to receive sand. The operation of making the mold in the manner above described is substantially as follows: The apparatus is operated so as to bring the pattern or stripping plate into the positions shown in Figs. 5 and 11, leaving the reservoir-space b ^{4} below the flask. The flask E is then placed upon the flask-table e and guided to position thereon and the feeding-reservoir H placed thereon. The sand is then fed from the hopper into the flask, filling the reservoir-space b ^{4} below the flask and extending up into the feeding-reservoir H. The operator then slides the feeding-reservoir over the flask and into the guideways h ^{2} , and by the cutter h' on the reservoir cuts or planes off the surplus sand, which passes down the chute h ^{2} , and so brings the top surface of the sand in the flask to the irregular shape of the flask—that is, the sand-surface corresponding to the shape of the top plate F—the top plate F then placed upon the flask and guided to place thereon, the horizontal beam G swung around by the handle g until its stirrup g' engages with the hook g ^{3} , and the hand-wheel g ^{6} is turned so as to force the resistance-plate F' into contact with the top plate F and hold the flask and said top plate solid ready for the making of the mold. The operator then

raises the trigger r^4 on the hand-lever L and pulls that hand-lever for the full stroke thereof, which through the connecting-rod p^3 raises the brake-shoe p^3 from the friction-drum P' 5 and through the connecting-rod N' operates the clutch to drive the power-shaft M through the pulley M^2 . The cam-shaft is then turned by the power-shaft, forcing the patterns and stripping-plate upwardly, the pattern first reaching its highest position and the stripping-plate following in its longer stroke, so that it is finally brought into line with the flask-plate e, thus completing the pressing operation. Meanwhile one of the knockers on 10 the disk R strikes the pivoted dog r^7 and carries around the vertical operating-shaft L', disconnecting the clutch, applying the brake, and bringing the hand-lever back to its normal position. The operator then draws down 15 on the lever K', withdrawing the pattern-blocks k from between the wing-patterns k' , said pattern-blocks k striking the arms k^4 of the wing-patterns and drawing the wings inwardly to the position shown in Fig. 8. The operator then pulls on the hand-lever L, applying the power, as above described, and causing the turning of the cam-shaft until another knocker on the disk R again operates, as above described, to turn the shaft L' 20 to free the clutch and apply the brake and to draw the hand-lever back to place, during which operation the pattern has been withdrawn from the pressed mold. He then raises on the lever K', forcing the block k between 25 the wing-patterns k' and spreading them into their normal position. He then raises the resistance-plate F', and by drawing on the hand-lever g carries the beam G back out of the way and leaves the table free from the removal of the mold. If a section of the continuous runner, such as illustrated in said 30 application Serial No. 449,904, is to be formed in the mold, this may be accomplished by forcing a cutter u through a guide-hole u' in the top plate F until it strikes the stripping-plate b. He then lifts it off the top plate F 35 and applies to the mold the guard-plate A ^{6} , by which it may be swung over and on which it will rest on the table T', this guard-plate having lugs engaging with the flask, so as 40 to hold the parts in proper line, and the rocker g ^{7} directing it over the hook g ^{2} on the table. The flask is then rocked over onto the side table, any cores required are 45 placed therein, and another flask may then be placed upon the flask-table e. The operator then draws up the lever L, which, operating as above described, causes the stripping-plate to be drawn down and, if necessary, the patterns to be raised and bring the machine back into position ready to receive sand. Sand is then fed to the new flask and the operation repeated. I am thus enabled 50 to form these molds having mold-faces on each side thereof rapidly and by unskilled labor, the only operations being the placing of the flask on the table, the feeding of the

sand thereto, the operations of certain levers, and the withdrawal of the flask containing the finished mold. Though the mold-faces 70 are of irregular shape, I am enabled by the cutting off of the sand surface corresponding to one face of the mold to provide proper proportions of sand above the pattern and stripping plate for packing and to bring one face 75 of the mold to practically the desired shape, so that there is no necessity of movement of that portion of sand in the pressing operation. By cutting off the sand to practically the shape of the finished mold and employing 80 the depressed pocket or reservoir below the flask K the apparatus can be arranged so that by the stroke both of the pattern and pattern-plate an even packing of the sand within the flask, sufficient to withstand the pressure of 85 the metal and yet permit proper venting of the mold, can be obtained. The mold parts can be made so rapidly that the expense of this class of molds is very materially reduced, and when employed with the continuous runner 90 extending through the series of molds on the foundry-floor and the downtake runners leading into the mold-cavities, as described in said application Serial No. 449,904, the necessity of skilled labor either for the making or pouring of the molds is done away with. At the same time I am enabled to form dovetailed recesses in the molds by a means which assures practically perfect formation thereof and the operation of the dovetailed pattern 95 parts simply by the movement of a lever.

The method disclosed herein is not claimed in this application, but is claimed in a divisional application filed February 1, 1901, Serial No. 45,591.

What I claim as my invention, and desire to secure by Letters Patent, is—

1. The combination with a table, of a flask or sand-holder resting thereon and a cutter having an irregular edge and adapted to slide 110 over the sand-holder and cut or plane off the sand corresponding to said irregular edge, and a guideway supported on the table and in line with the flask edge to support the cutter in its movement, substantially as set forth. 115

2. The combination with a flask or sand-holder having an irregular edge portion, of a cutter having an irregular edge corresponding to such edge portion and adapted to slide over the sand-holder and cut or plane off the 120 sand corresponding to the edge thereof, substantially as set forth.

3. In sand-molding apparatus, the combination with a flask or sand-holder of irregular shape, of a sand-reservoir corresponding in 125 shape to the sand-holder and sliding over the same so as to cut or plane off the sand to the shape of the flask, substantially as set forth.

4. The combination with a flask or sand-holder having an irregular edge, of a cutter having an irregular edge corresponding in shape to that edge, and having guides to hold it in line with the sand-holder said cutter adapted to slide over said flask and cut or

plane off the sand to the shape of the edge thereof, substantially as set forth.

5. The combination with a table, a flask or sand-holder resting thereon having an edge 5 of irregular shape, and a cutter adapted to slide over the sand-holder and cut or plane off the sand corresponding to said irregular edge, and a guideway supported on the table and in line with the flask edge to support the cutter in its movement, substantially as set forth.

6. In combination with the molding-table, a flask having its lower edge of irregular shape, a flask-supporting plate on the table having its face corresponding to the lower edge of the flask, and a pattern adapted to be forced into the flask, substantially as set forth.

7. The combination with a table, of a flask having its upper and lower edges of irregular shape, a flask-supporting plate on the table and having its face corresponding to the lower edge of the flask, a confining-plate on the flask having its inner face corresponding to the upper edge of the flask, and a pattern adapted 25 to be forced into the flask, substantially as set forth.

8. The combination with a table, of a flask having its lower edge of irregular shape, a flask-supporting plate on the table and having its face corresponding to the lower edge of the flask, a confining-plate on the flask, a pattern adapted to be forced into the flask, and a stripping-plate fitting around the pattern and corresponding in shape to the lower 35 edge of the flask, substantially as set forth.

9. The combination with a table, of a flask having its upper and lower edges of irregular shape, a flask-supporting plate on the table and having its face corresponding to the lower edge 40 of the flask, a confining-plate on the flask, having its inner face corresponding to the upper edge of the flask, a pattern adapted to be forced into the flask, and a stripping-plate fitting around the pattern and corresponding in shape to the lower edge of the flask, substantially as set forth.

10. The combination of a table, a flask having its lower edge of irregular shape, a flask-supporting plate on the table and having its face corresponding in shape to the lower edge 50 of the flask and having a flange depending from its inner edge and forming a pocket in the reservoir, a vertically-movable stripping-plate corresponding to the lower edge of the flask and fitting within the depending flange and forming the base of the reservoir and a vertically-movable pattern extending up within said stripping-plate, substantially as set forth.

60 11. The combination with a supporting-frame, a hollow pattern vertically movable therein, wing-patterns pivotally mounted in the hollow pattern and extending up through the top thereof and having inwardly-projecting lugs at their lower ends, and a pattern-block having recesses into which the said lugs extend, adapted to be raised to spread the

wing-patterns, and hold them in molding position and to be drawn down and contact with the lugs and draw the wing-patterns together 70 for the withdrawal of the pattern from the mold, substantially as set forth.

12. The combination with a supporting-frame, of hollow patterns vertically movable therein and carried by a pattern-frame, wing-patterns mounted in and extending up through the top of the hollow patterns, pattern-blocks sliding within the hollow patterns and adapted to be forced between the wing-patterns, and a plate below the pattern-frame 80 connected by bars with the pattern-blocks and connected by a strap to a lever mounted on a bar depending from the pattern-frame, substantially as set forth.

13. The combination with a supporting-frame, of a hollow pattern vertically movable therein, and carried by a pattern-frame, wing-patterns, mounted in the hollow pattern and extending up through the top thereof, a pattern-block sliding in the hollow pattern and 90 adapted to be forced between the wing-patterns to hold them in molding position, bars depending from the pattern-frame and having a lever mounted therein, a strap connecting said pattern-block with the lever, and 95 stops on one of said bars depending from the pattern-frame limiting the movement of the lever, substantially as set forth.

14. The combination of a main frame, a vertically-moving pattern-frame mounted therein and carrying a pattern, cam mechanism engaging with said frame and adapted to raise the same and force the pattern into the sand within the flask, a weighted withdrawing-lever connected to said pattern-frame to 105 insure the withdrawal of the pattern from the mold, and a separate cam controlling the movement of said weighted lever, substantially as set forth.

15. The combination of a main frame having a table, a hook on the top thereof, a flask resting on the same, a pattern entering the flask from below, a top confining-plate, a swinging frame adapted to engage with the top confining-plate and having a stirrup engaging with said hook, and a rocker on the table at the end of the flask adapted to direct the same over said hook when the flask is rocked over, substantially as set forth.

16. The combination of a main frame, a 110 table, a flask resting thereon, a pattern entering the flask, a rocker on the table to support the flask as it is rocked over, and a guard-plate adapted to be placed upon the flask and having guiding-lips to hold the flask and 115 guard-plate in line as it is rocked over, substantially as set forth.

17. The combination of a main frame, a vertically-movable pattern carried by a pattern-frame mounted therein, an arm or lever carried by said frame, an operating-shaft controlling the driving mechanism, said shaft having a locking-arm thereon, and a locking-bar with which the arm on the pattern-frame

is adapted to contact to cause such locking-bar to engage with the locking-arm on the operating-lever, substantially as set forth.

18. The combination of a main frame, a vertically-movable pattern carried by a pattern-frame mounted therein, an arm or lever carried by said frame, an operating-lever controlling the driving mechanism, said lever having a locking-arm thereon, a locking-bar pivoted on the main frame in the course of the lever on the pattern-frame and having a lip in the course of the locking-arm on the operating-shaft, and a spring holding the locking-lip on said locking-bar out of the course of the locking-arm on the operating-lever, substantially as set forth.

19. The combination with a main frame, a vertically-movable pattern mounted therein operated by power connections, a supplementary pattern on the main pattern, a lever mounted on the pattern-frame and operating the supplementary pattern by the vertical movement of the lever, a shaft controlling the driving mechanism having the locking-arm thereon, and a locking-bar engaging with said locking-arm and extending in the course of the lever carried by the pattern-frame, substantially as set forth.

20. The combination of a main frame, a vertically-movable pattern carried by a pattern-frame mounted therein, an arm or lever carried by said frame, an operating-shaft controlling the driving mechanism, said shaft having a locking-arm thereon, a locking-bar with which the arm on the pattern-frame is adapted to contact to cause such locking-bar to engage with the locking-arm on the operating-lever, and a spring connected to the locking-bar and holding it normally out of the course of the locking-arm, substantially as set forth.

21. The combination of a main frame, a pattern-frame mounted therein and carrying a pattern, driving mechanism for imparting vertical movement to the pattern-frame, a supplementary pattern mounted in the main pattern and connected to a lever mounted in the pattern-frame, an operating-lever controlling the movement of the driving mechanism and carrying the locking-arm, and two locking-bars extending one above and the other below the lever carried by the pattern-frame and held normally out of the course of the locking-arm on the operating-lever but adapted to be thrown into such course by said lever on the pattern-frame, substantially as set forth.

22. The combination of a main frame having a cam-shaft, a pattern carried by a frame operated by the cam on said shaft, an operating-shaft controlling the driving mechanism, a knocker on the cam-shaft, and a dog carried by the operating-lever extending in the course of the knocker on the cam-shaft, substantially as set forth.

23. The combination of a main frame having a cam-shaft, a pattern carried by a frame operated by the cam on said shaft, an oper-

ating-shaft controlling the driving mechanism, a knocker on the cam-shaft, and an arm carried by the operating-shaft, said arm having a movable dog extending in the course of the knocker on the cam-shaft substantially as set forth.

24. The combination of a main frame having a cam-shaft, a pattern carried by the frame operated by the cam on said shaft, an operating-shaft controlling the driving mechanism, a knocker on the cam-shaft an arm carried by the operating-shaft, said arm having a movable dog extending in the course of the knocker on the cam-shaft, and a trigger connected to said dog and adapted to withdraw the same from the course of the knocker, substantially as set forth.

25. The combination of the main frame having a cam-shaft D mounted therein and operating one or more patterns mounted in said frame and carrying the disk R having knockers r thereon, the vertical shaft L' having the hand-lever L, the arm l' on said shaft L' having the dog r' mounted therein, and the trigger r' mounted on the hand-lever L connected to the dog, and the spring r holding said dog normally in the course of the knockers on the disk, substantially as set forth.

26. The combination of a main frame having a pattern mounted therein, the driving-shaft M, and operating mechanism between the same and the pattern for moving the pattern a power-driven pulley on the driving-shaft, clutch mechanism connecting said shaft and the pulley, the operating-shaft L' carrying the arm l, the lever N connected to the clutch, the strap N' connecting said lever and the arm l on the vertical shaft L', and knocking mechanism for turning the shaft L' and freeing the clutch, substantially as set forth.

27. The combination of the main frame having a pattern mounted therein, a cam-shaft D operating said pattern and having knockers thereon, the driving-shaft M turning the cam-shaft, a power-driven pulley on said driving-shaft and clutch mechanism between the shaft and pulley, the operating-shaft L' connected to the clutch, and a dog carried by the operating-shaft in the course of the knockers on the cam-shaft, substantially as set forth.

28. The combination of a main frame, a pattern therein, a cam-shaft for moving said pattern, a driving-shaft turning the cam-shaft, a power-driven pulley on said driving-shaft, clutch mechanism between the pulley and the shaft, a brake operating on said driving-shaft, and an operating-shaft having connections therefrom to the clutch mechanism and to the brake for applying the clutch and releasing the brake, or vice versa, substantially as set forth.

29. The combination of a main frame, a pattern mounted therein, mechanism for operating the pattern, a driving-shaft connected to said mechanism and carrying a friction-drum, a brake operating on said friction-drum, and an operating-lever controlling the movement

of the driving-shaft, and connections from said operating-lever acting to withdraw the brake from the friction-drum, substantially as set forth.

- 5 30. The combination of the driving-shaft carrying the friction-drum P' , the weighted brake-bar pivoted in the frame and carrying the brake-shoe p^3 , the sliding bar p^4 extending through a guide over the forward end of 10 the brake-bar and having an inclined face thereon for forcing down that end of the brake-bar and so raising the shoe, and the operating-shaft L' connected to said sliding bar p^4 , substantially as set forth.
- 15 31. The combination of a main frame having a pattern mounted therein, the cam-shaft operating said pattern and having a knocker thereon, a driving-shaft turning the cam-shaft, clutch mechanism connecting a power- 20 driven pulley with said driving-shaft, braking mechanism operating on said driving-shaft, and an operating-shaft controlling said clutch mechanism and braking mechanism

and having a dog in the course of the knocker on the cam-shaft, substantially as set forth. 25

32. The combination of a series of flasks, each adapted to stand on one of its ends on the molding-floor and in contact with each other, said flasks each having supporting-bearings on only one side of the lower end 30 thereof so as to cause each flask to swing or press against the adjoining flask, substantially as set forth.

33. In combination with the support, a flask having its lower edge of irregular shape, a 35 flask-supporting plate on the support, having its face corresponding to the lower edge of the flask, and a pattern adapted to be forced into the flask.

In testimony whereof I, the said STEPHEN 40 JARVIS ADAMS, have hereunto set my hand.

STEPHEN JARVIS ADAMS.
